UNITED STATES PATENT OFFICE.

WILLIAM L. MONRO, OF PITTSBURGH, PENNSYLVANIA, ASSIGNOR TO WINDOW GLASS MACHINE COMPANY, OF PITTSBURGH, PENNSYLVANIA, A CORPORATION OF NEW JERSEY.

DRAWING GLASS SHEETS.

Application filed April 23, 1920. Serial No. 375,972.

To all whom it may concern:

Be it known that I, WILLIAM L. MONRO, of Pittsburgh, Allegheny County, Pennsylvania, have invented a new and useful Improvement in Drawing Glass Sheets, of which the following is a full, clear, and exact description, reference being had to the accompanying drawings, forming part of this specification, in which—

10 Figure 1 is a diagrammatic longitudinal section showing a portion of the apparatus arranged for carrying out my invention;

Figure 2 is an elevation showing one form of the bending rolls and tension rolls;

15 Figure 3 is a view similar to Figure 2, showing another form of the bending rolls; and

Figure 4 is a diagrammatic view illustrating another modification.

20 My invention relates to the drawing of sheet glass and particularly to the continuous drawing of sheet glass over a bending roller by which it is bent from a generally vertical direction to a generally horizontal direction.

25 In such a drawing operation, it has been found that the bending roll makes defective glass, the roll surface imparting surface defects, such as pimples, embedded foreign matter, etc., to that sur-

30 face of the sheet which contacts therewith. My invention is designed to overcome this difficulty, and consists in providing a bending roll system which avoids contact of the roll system with the greater portion of the

35 glass sheet, the thickened edge portions of the sheet being the only ones which contact with the bending roll system.

In the drawing, referring to the form of Figures 1 and 2, 2 represents the end portion 40 of a tank furnace which extends to the right of the figure. 3, 3 are water coolers to cool and set the rising sheet. The sheet is preferably drawn with thickened edge portions which are preferably engaged just above the

45 meniscus by friction brake devices, shown as pairs of rolls 4, 4, projecting inwardly from the sides and engaging these thickened edge portions. These stub rollers may be provided with any suitable amount of

50 friction or drag by brake devices applied to their portions exterior to the drawing chamber. They thus impart any desired amount of drag or tension to the sheet as it rises. In this form, 5, 5 indicate two bending rolls forming a bending roller system which en-

gage the thickened edge portions of the sheet, these being mounted on stub shafts 6, 6, which project to the exterior of the drawing chamber and may be driven synchronously at any desired speed.

After passing over the bending roll system, the sheet is drawn horizontally, preferably through a flattening chamber, and then through an annealing chamber, by any desirable means.

55 In Figure 3, I show a form similar to Figure 2, except that the bending rollers 5^a are secured to a sleeve 7 splined to a continuous shaft 8, extending through the drawing chamber. In this case, of course, power may be applied to one end only of the bending roll system if it is desired to drive the same.

70 Instead of drawing the sheet by grippers or power applied after passing the bending roll, I may draw the sheet by gripping its edge portions between edge rolls 5^b and driven rolls 9, as shown in Figure 4. In this case, the rolls 9 will preferably be stub rolls or separated rolls, such as shown in Figures 2 and 3, and engaging substantially only the thickened edge portions of the sheet. These tend to stretch the sheet and keep it from sagging between these rollers.

75 80 85 Suitable heating burners may be applied wherever desired in the drawing chamber to assist in reheating the glass for bending or for any other purpose.

90 The advantages of my invention result from the use of a bending roll system which avoids contact of the bending roller with the glass sheet proper, the bending being effected by engaging the thickened edge portions which are removed after the glass has passed through the annealing leir and cut into sheets. I thus avoid the marring or defacing of the bending roll side of the continuous glass sheet by action of the bending roll surface thereon. If the sheet tends to sag down between the bending rolls, this will be overcome in the succeeding flattening operation, which may be carried out by the flattening devices indicated at 10 and 11 in Figure 1.

100 105 110 The bending roll system may be driven or not, as desired, the track rolls may be driven or not, as desired, and many other changes may be made without departing from my invention, since I consider myself the first to employ a bending roll system

for this purpose wherein contact is avoided between the bending roll and the under surface of the glass sheet.

I claim:

- 5 1. In apparatus for drawing sheet glass in a generally vertical direction and thence in a generally horizontal direction, means for imparting thickened edges to the sheets, and a bending roll system engaging said thickened edge portions and out of contact with the sheet proper, substantially as described.
- 10 2. In apparatus for drawing sheet glass in a generally vertical direction and thence in a generally horizontal direction, a drag roll system arranged to impart a tension to the glass sheet, and a bending roll system arranged to contact with the under surface of the edge portions only of the sheet, substantially as described.
- 15 3. Apparatus for drawing sheet glass, comprising a bath from which a sheet of glass is drawn, a pair of bending roll portions engaging the edge portions only of a drawn sheet, the bending roll portions being a substantial distance above the bath, and width maintaining means associated with each sheet edge adjacent the bath.
- 20 4. Apparatus for making sheet glass, comprising a source of molten glass, a plurality of spaced apart bending roll portions adapted to change the direction of travel of a sheet formed at such source, the portions of the sheet between such bending roll portions being out of contact with the bending roll, and means associated with the sheet edges adjacent such source for maintaining the width of the sheet.
- 25 5. Apparatus for making sheet glass, comprising a source of molten glass, a plurality of spaced apart bending roll portions adapted to change the direction of travel of a sheet formed at such source, the portions of the sheet between such bending roll por-

tions being out of contact with the bending roll, and means adjacent the source for maintaining the width of the sheet, said means engaging the same portions of the sheet as are afterwards engaged by the bending roll portions.

6. Apparatus for drawing sheet glass, comprising a bath of molten glass, means for reducing the temperature of a portion of such bath so as to define a region of lower temperature from which a sheet of glass may be drawn, a plurality of bending roll portions spaced from said bath and so positioned as to draw a sheet from the region of lower temperature in the bath, the bending roll portions being spaced apart and adapted to change the direction of travel of the sheet, the portion of the sheet between such portions being out of contact with the bending roll, and means associated with the sheet edges adjacent the bath for maintaining the width of the sheet.

7. Apparatus for drawing sheet glass, comprising a bath of molten glass, means for reducing the temperature of a portion of such bath so as to define a region of lower temperature from which a sheet of glass may be drawn, a plurality of bending roll portions spaced from said bath and so positioned as to draw a sheet from the region of lower temperature in the bath, the bending roll portions being spaced apart and adapted to change the direction of travel of the sheet, the portion of the sheet between such portions being out of contact with the bending roll, and width maintaining means adjacent the bath, said means engaging the same portions of the sheet as are afterwards engaged by the bending roll portions.

In testimony whereof I have hereunto set my hand.

WILLIAM L. MONRO.
